UNITED STATES PATENT OFFICE.

BORBÁLA SZILLI GOSZTOLA, OF SOUTH BEND, INDIANA.

DESIGN FOR A STOCKING.

47,847.

Specification for Design.

Patented Sept. 21, 1915.

Application filed March 25, 1915. Serial No. 17,060. Term of patent 7 years.

To all whom it may concern:

Be it known that I, BORBÁLA SZILLI Gosztola, a subject of the King of Hungary, residing at South Bend, in the county of St. Joseph and State of Indiana, have invented a new, original, and ornamental Design for Stockings, of which the following is a specification, reference being had to the accompanying drawing, forming part thereof.

The figure is a perspective view of a stocking, showing my new design.

I claim:

The ornamental design for a stocking, as shown.

BORBÁLA SZILLI GOSZTOLA.
